UNITED STATES PATENT OFFICE

113,815

DESIGN FOR A DRESS

Joseph Levay, New York, N. Y.

Application January 18, 1939, Serial No. 82,417

Term of patent 3½ years

To all whom it may concern:

Be it known that I, Joseph Levay, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

My design is characterized by the specific sleeve member in combination with the specific neckline on the pleated dress disclosed.

I claim:

The ornamental design for a dress, substantially as shown, and described.

JOSEPH LEVAY.
